UNITED STATES PATENT OFFICE

EDMONDSON SPENCER, OF CALCUTTA, BRITISH INDIA

APPARATUS FOR AND PROCESS OF SEPARATING OR EXTRACTING CELLULOSE OR PAPER PULP

Application filed February 10, 1928, Serial No. 253,310, and in British India May 28, 1927.

This invention relates to improvements in the separation or extraction of cellulose or paper-pulp from bamboo, wood, grasses, reeds or other suitable fibre yielding vegetable material by processes involving the treatment of the said materials with caustic or other digesting liquors in digesters.

The invention relates mainly to apparatus for carrying out improved processes of separation or extraction of cellulose. It is more particularly applicable to providing apparatus for carrying out the processes claimed in Patent No. 1,690,954, dated November 6, 1928, but it is not limited to apparatus for carrying out such processes alone owing to the applicability of the apparatus (which will be described in detail hereinafter) to other processes and to developments and modifications of the said processes.

Certain modifications and developments of the said process are also included within the scope of the claims appended hereto.

This invention comprises apparatus for the semi-continuous extraction or separation of cellulose or paper pulp from bamboo, grasses, wood, reeds or other fibre-yielding vegetable material adapted to work on a digestion process on the cascade or progressive system, such for example as any of these processes claimed in the above mentioned Patent No. 1,690,954 or a process as set forth hereinafter, wherein the digesters are linked up in a ring or closed circuit adapted to work on a principle analogous to that known in the chemical industry as reverse washing or the counter-flow principle, wherein the stock is loaded in turn into each digester in the ring and the stock in any one digester is subjected therein successively to a series of treatments with

caustic or other liquor in successively increasing active chemical concentrations each treatment being at a higher pressure and temperature than the last until the digestion is complete, and the stock or pulp, still in the same digester, is subsequently leached, preferably first with used and heated leaching liquor which has been used at least once before, and finally with one or more washes of water, the digester being then unloaded of its pulp and reloaded with a fresh charge of cellulose con-

taining stock, characterized in that the caustic or other digesting liquor used in the digestion in any one digester with such non-cellulosic matter dissolved out and carried by the same is passed from that digester to the next—but one digester in operative sequence under digestion in the cycle working at a lower pressure and free caustic or digestion liquor concentration.

In this apparatus the digesters are connected in a ring or closed circuit having ring pipe or trunk connections and the necessary cocks and valves, whereby the liquor in any one digester may be transferred to any other digester in the ring, and further connections are provided whereby any digester in the ring may be supplied with steam, wash water or digesting liquor and whereby the spent liquors may be drawn off.

In the preferred embodiment the digesters are connected up in a double ring, and two ring pipes or trunks for transferring digester liquor, make up liquor or wash water to and from the digestion in the double ring are provided, characterized by alternate digesters in the double ring being connected to alternate ring pipes by suitable valves and cocks so arranged that the alternate digesters may be operated independently in their closed ring circuits, suitable steam, liquor and wash water or the like connections being provided and connections for drawing off spent liquors.

Whereas two rings may be provided for digesting liquor and wash or make-up water only a single live-steam ring pipe and a single spent-liquor-discharge ring pipe need be provided with connections from the last two ring pipes to all the digesters.

The apparatus also may include the feature according to which connection from the wash water-tanks are made to both liquor transferring rings with cocks, preferably pumps also, controlling the supply, and wherein separate tanks are provided similarly connected to both such rings for receiving the first wash water and the second or subsequent wash water respectively, the arrangement being such that wash water which has been used at least once for wash-

ing out or leaching the contents of a digester (the digestion in which is completed and which has been partially washed already) may, after use in the primary or an early 5 washing of the next digester the digestion in which is finished, be transferred or pumped into the tank for receiving the second or several-times-used wash-water, connections being provided whereby the said wash-water 10 from the last mentioned tank may be pumped or transferred as a primary wash to another digester the digestion in which is subsequently finished, or be used as make-up liquor in any of the digesters in the system.

15 In the apparatus according to this invention the arrangements may be such that, whilst the digestion is arranged to be carried out in steps or stages the pressure and/or the free caustic or active liquor concentration 20 being increased or modified progressively in each successive step or stage, the transfer of or the blowing down of digestion liquor from one digester to another in the digestion may take place simultaneously with a similar operation carried on between two other digesters, which second pair are in the alternate ring and in an overlapping stage of their 25 digestion process.

Moreover, the apparatus may be so arranged or modified that economy in time and 30 in labour and in the continuous utilization of the services of the staff may be effected by the simultaneous transfer or blowing over of liquors between two pairs (or more than 35 two pairs, if the plant is sufficiently extensive and suitably arranged) of digesters at a time, owing to the processes being made to over-lap each other by sufficient amounts to allow the said staff to make all the necessary connection 40 for the operation between any pair of digesters, and, whilst said operation is in progress, turn their attention to the making of the necessary connections for the operation between a second pair (or other pairs) of 45 digesters.

The invention also includes within its scope a process of semi-continuous extraction or 50 separation by digestion of cellulose or paper pulp from material containing the same, which is adapted to be carried out in apparatus as herein explained, or is a modification 55 of the kinds of processes such as are claimed in the previously mentioned Patent No. 1,690,954 but is characterized by the feature that, the digesters being linked up in two rings, or in a double ring alternate digesters being adapted to be connected to alternate rings for the purposes of being blown over, a method of operation is available 60 wherein, owing to the said two or double ring system being used, two digesters connected to one ring may be transferring the liquor or liquid contents one to the other simultaneously as two digesters in the other ring are similarly operating, whereby a saving of time

may be effected and the loading and unloading of the digesters be facilitated.

The invention also includes such a process but wherein two pairs of digesters are simultaneously transferring their liquid contents 70 one to the other, or wherein at least one pair is being operated in this manner and another digester is simultaneously discharging its spent liquors to the recovery plant or other desired destination, characterized by the feature that the transfers of the said liquid contents are over-lapped by sufficient amount to allow the staff to make all the necessary arrangements or connections for the one transfer to start or for that transfer to take place 75 in over-lapped relation to the start or the carrying out of the other transfer, said second transfer being in its turn over-lapped with a third transfer, and so on, for the purpose of utilizing the time and service of the 80 staff to the greatest efficiency.

A preferred form the apparatus may take is described with reference to the accompanying drawings in which:—

Fig. 1 is a diagram of a typical battery 90 adapted to work in a ring or closed continuous circuit on the cascade principle.

Fig. 2 is a detail of the connections.

This system is shown employing a step-down pressure arrangement with an alternate ring series from the highest pressure digesters containing the strongest free caustic liquor and almost completely leached stock— 95 to the lowest pressure digesters with spent liquor and newly charged stock.

Figure 1 illustrates diagrammatically the arrangement with eight digesters in the cascade system Nos. 1—2—3 . . . 8 being the digesters with alternate ring pipe connections to ring mains R^1 and R^2 . Digesters 100 Nos. 1, 3, 5 and 7 are connected to ring R^2 whilst Nos. 2, 4, 6 and 8 are connected to ring R^1 .

Digester No. 1 is starting with bamboo or other fibrous material on its last stage of digestion under full pressure and with fresh strong caustic or other suitable digesting liquor supplied from the caustic or liquor tank C.

We will assume that 20% of the digestible material is removed at each stage of the digestion and that the last 20% still remains to be removed at the commencement of full pressure digestion in No. 1.

Similarly the material in digesters Nos. 2, 120 3, 4 and 5, is at the same time under extraction, No. 5 being at the lowest pressure and extracting the first 20% of digestible matter. No. 4 is under a higher pressure than No. 5 and is removing the second 20%, and so on.

When digestion in No. 1 is complete digester No. 2 is ready for its last extraction with clean fresh caustic. No. 3 digester is ready for its last-but-one digestion with only once used liquor i. e. with liquor from No. 1.

Similarly No. 4 is ready for liquor from No. 2 and No. 5 for liquor from No. 3. No. 6 has in the mean time been loaded with fresh stock.

To operate the cycle between No. 4 and No. 6 the ring cocks 1 and 2 are opened and the liquor is blown over from No. 4 to No. 6. This is done by utilizing the pressure in No. 4 which is considerably higher than the pressure in No. 6 which latter will generally be open to atmosphere for the greater part of this step in the process. At the same time the waste cock 4 of No. 5 is opened and the liquor contained therein is blown out, using the residual pressure in No. 5, to the recovery through pipe 6. When the digester liquors have been completely blown over from Nos. 4 and 5 digesters the ring cock 1 of No. 6 and the waste liquor cock 4 of No. 5 are closed, but ring cock 2 is still left open, and ring cocks 7, 8 and 9 of Nos. 2 and 3 and 5 are opened and the liquors blown over from Nos. 2 and 3 to Nos. 4 and 5 respectively. Cocks 1 and 9 of Nos. 4 and 5 are then closed and the ring cock 10 of No. 1 is opened and its liquor (ring cock 8 still remaining open) is blown over to No. 3 along with some make-up wash liquor from the wash-water tank W2 by opening the corresponding wash-water cock 11. Make-up liquor can also be added in the same way to digesters Nos. 4 and 5 if necessary, to accommodate or completely cover the greater volume of the less digested stock.

At the same time fresh heated caustic is pumped or blown under pressure into digester No. 2 from the caustic tank C through pump 19 and cocks 12 and 7. No. 1 digester is now ready for its first wash. This is also pumped under pressure through pump 20, cocks 13 and 10 from the wash-tank W1 which contains the second wash or the first water-wash of No. 8. This wash is then sent from No. 1 digester to tank W2 through cocks 10 and 11 to be used subsequently as make-up for No. 4 etc. No. 1 digester then receives its second wash or first water wash. The water is pumped from tank W through pump 14, and cocks 15 and 10 and this wash liquor is sent to tank W1 in readiness for the first wash of No. 2. The contents of digester No. 1 are now partly cooled owing to a good part of the heat locked up in the pulp having been extracted by the wash water sent on to tanks W2 and W1 respectively, the heating of which water adds to the economy of the system in that it reduces the call for live steam for make-up purposes in digester No. 3 etc. The drain cock D is then opened and the contents of the digester are flushed with water and finally unloaded.

No. 8 has been unloaded and No. 7 loaded in the meantime in readiness for the next cycle of operations.

The two outer pipe rings R3 and R4 represent the recovery pipe and the steam pipe rings respectively. The recovery pipe 6

takes spent liquor from the first extraction to the recovery plant via an economizer if desired. The steam pipe ring R4 supplies steam to the digesters as required to keep them up to their respective digestion pressures. Let us assume that the process is working on bamboo and that the final digestion in No. 1 digester has been carried out at 100 lbs. pressure (170° C.). No. 3 digester has finished its third or last-but-two digest at 60 lbs. pressure (153° C.) and has blown its liquor over to No. 5. The residual pressure in the digester No. 3 is say 25 lbs. (130° C.). No. 1 liquor is blown into it with the result that the pressure in No. 1 drops say to 60 lbs. and that in No. 3 rises to 50 lbs. (148° C.). After closing No. 3 live steam is introduced from steam ring R4 through cock 16 into No. 3 digester by opening this steam cock sufficiently long to bring the pressure up to the desired amount viz., 80 lbs. (162° C.) and additional steam is supplied if desired to keep up this pressure over the extraction period.

With a residual pressure of 60 lbs. in No. 1 when its digestion is complete it is necessary to pump the wash-water already used once before from tank W1 into No. 1.

After the first wash of No. 1 the wash-water (already used twice) is pumped or transferred into tank W2 to be used as make up liquor for other tanks such as No. 4 being already mixed with the digesting reagents recovered from Nos. 8 and 1 and heated up to a considerable extent.

No. 1 will have now dropped in pressure considerably and its second wash will take place with water from water tank W this water being pumped into or transferred to No. 1 which now has really become No. 8 as the digesters numbers change in rotation as the process proceeds.

The wash-water after the second wash of No. 1 (now No. 8) is transferred to tank W1 but has little pressure. It is however heated up in the process of washing and adds to the heat economy of the system.

Little heat is really lost in the process of washing and the greater part of the heat after the final digestion is complete is recovered in this process.

It is of course understood that the pressures indicated above for bamboo may themselves be widely varied and are only given by way of illustration and may be modified to suit the optimum conditions for the particular kind of fibrous material undergoing digestion and for the kind of digester liquor used.

In the above description of the operation of a cycle, it has been assumed for simplicity that the connection to the digesters from the alternate ring pipe systems R1 and R2 was made to the bottom of each digester via a single valve. Thus in "blowing over" a di-

gester the liquor would pass from the bottom of the one digester to the bottom of the other.

In actual practice and if using the Sinclair type of digesters (which is one having internal vomit pipes) the "blow over" would be more effective if made to proceed from the bottom of the blowing off digester to the top of the receiving digester.

This result readily is obtained by means of a branch connexion from the ring pipe system R1 or R2 to the top and bottom of each digester, with a valve 17 and 18, in each branch as shown in Figure 2.

If digester A (Fig. 2) for example is blowing liquor over to another digester the lower cock 18 would be opened to the pipe ring R1 (or R2 as the case might be) and the upper one 17 closed, while if receiving liquor from another digester, the upper cock 17 would be opened and the lower one 18 closed.

It may be desirable to precede the treatment of the stock with caustic by a treatment with boiling water, because by such prior treatment caustic may be economized owing to said hot water dissolving out the water-soluble constituents in the stock which would otherwise consume a portion of the digesting reagent. In this cascade system this preliminary washing is easily effected as will readily be apparent. All that is necessary is to concentrate the washing, unloading and loading operations in digesters Nos. 8 and 7 instead of in three digesters, so that No. 6 is then available for a preliminary treatment with hot water to dissolve out the water-soluble constituents before it receives its first charge of nearly spent caustic liquors from No. 4. The water for washing out No. 6 may be obtained from wash-water tanks W1 and W2 and would thus be more or less heated already. More water and further wash water tanks would in that case be used in washing Nos. 1 and 8 than otherwise in order to supply extra water in these two tanks W1 and W2 not only for use as make-up liquor for digesters Nos. 3, 4 and 5 but also to supply the water for No. 6. The water for the preliminary treatment of digester No. 6 might however be supplied from tank W or from other source, and the same be heated up to the required temperature in No. 6 by admitting live steam through cock 21 from the steam ring R4.

From the above description of the process and a consideration of the diagram, it will be evident that the double ring cascade system of extraction can be arranged with any even number of digesters from four upwards. In most plants eight or ten digesters will be the preferred number.

The proportional number of digesters under extraction out of the total number in the cascade system can also be varied from two or three upwards, as may be found necessary to meet the requirements of the particular material to be digested.

Similarly, the number of digesters in the washing, unloading, and loading and preliminary treatment-with-water sections of the cascade system can be regulated to suit the conditions of the particular operation in each case. The desideratum will be that any particular operation in the cycle should not be responsible for a hold-up in the continuous uninterrupted operation of the system. Thus, with hydraulic or other mechanical methods of unloading, one digester in the unloading section of the system would probably be sufficient; whereas with hand unloading and the prolonged cooling period which would be necessary, two, or even three digesters might be required in the cooling and unloading section of the system.

For some types of fibre such as bamboo it may also be found advantageous to lay more stress on the preliminary treatments and to give the raw material both a preliminary hot water wash or/and a boil with very weak alkali solution. The insertion of one or more digesters in the cycle between the loading digester No. 6 and the 1st extraction digester No. 5 (using liquor) would provide for this and the earlier washes from the finished digester No. 1 could be collected for a weak alkali boil, if this was found to be necessary, whilst the water from the last wash of all in No. 8 might be used for the preliminary hot water extraction.

It will be noted that a great saving of time and saving in the utilization of the services of the staff may be effected by using this plant.

Digestion may be proceeding practically continuously in the five or other number of stages selected.

In the ordinary systems of working there is great delay and part of the staff may be largely unoccupied whilst digestion is proceeding and only become really active when a digester is being blown down or refilled. According to this plant and process the ring connections R1 R2 are readily made and the rings and valves may be of large size so that it may take say only five or ten minutes to blow out the liquor from a large digester, and another five or ten minutes say, to blow in stronger liquor and raise the pressure to a desired level. But the connection for either of these steps having been made the staff can then make suitable connections for a similar operation to be effected practically simultaneously but in over-lapped relation between another pair of digesters, or between two other pairs if desired, before the particular blowing over between the digesters of the first pair is complete, thus utilizing the time of the staff fully and speeding up the operations. A considerable saving may be effected by working in the manner suggested. For example, whilst spent liquor from No. 5 is being run

off to waste, and stronger liquor at higher pressure from No. 3 is being blown into No. 5, simultaneously but following a little later liquor from No. 4 may be blown into No. 6 and subsequent (but over-lapping the final operation between No. 3 and No. 5) liquor from No. 2 may be blown into No. 4. Thus first No. 5 and then No. 4 (both being digesters in an early stage of the digestion operation 10 and hence being in what may be termed approximately the same stage of digestion) are started on their digestion period one after the other. A similar overlapping is to be observed in the latter stages of the digestion and 15 in the operations of the staff in keeping the operations moving in proper sequence around the ring.

It should further be noted that another great advantage obtainable by using a double 20 ring over that obtained by using a single ring is that the loading and unloading is made more regular when the double ring is used. This may be realized from the following:—

Assuming the first four digesters are part 25 of a single ring. No. 1 unloading—No. 2 loading—No. 3 on its first digest—No. 4 on its third digest. When the time is ready for Nos. 3 and 4 to blow over, the liquor in No. 3 is completely used up and goes to the recovery. 30 The liquor in No. 4 digester, having finished the third digest of its bamboo, is blown over to No. 3 to start the second stage in the digest of the bamboo in that digester. There is no liquor ready to carry out the first digest in the 35 freshly loaded No. 2 digester and it has to lie fallow until the second stage of digestion has been carried out in No. 3 digester. On the other hand, if there had been a double ring, the newly loaded digester would have been in 40 the alternate ring and the digester immediately in front of it in sequence would have been undergoing its second digest, so that, the liquor would have been blown over to the loaded digester without any delay. Of 45 course, we might have assumed in the above four digesters that Nos. 3 and 4 were undergoing their second and fourth digests, in which case, the liquor from No. 3 would have been blown over directly to No. 2, but this 50 would merely push the delay forward on to No. 1 digester after it had been loaded.

In other words, with a single ring, there would be a delay after loading each alternate digester (and the same at the washing stage). 55 This delay is avoided by using a double ring, as, what would be the delay period in each ring corresponds to the loading period in the other.

It will of course be understood that, although the invention has been described in relation to a particular lay-out of plant which has been found convenient, it is not by any means restricted in its application to the particular plant referred to, as it will be obvious that, given suitable piping, trunks, con-

nections and valves, the process could be worked with very different arrangements of plant. The plant actually described moreover may be modified by introducing extra piping, tanks and pumping means if it is desired to develop the washing and preliminary treatment parts of the process. 70

Having now particularly described and ascertained the nature of my said invention and in what manner the same is to be performed, I declare that what I claim is:— 75

1. Apparatus for the cascade extraction of cellulose pulp from fibre yielding vegetable material comprising a plurality of digesters, ring trunks linking up said digesters in a closed circuit, connections between said digesters and said ring trunks whereby liquor in any one digester may be transferred to any other digester, means connected to said digesters and said ring trunks whereby any 85 digester may be supplied with make up liquor, wash water and digesting liquor, means for supplying steam to said digesters, and means connected to said digesters whereby the spent liquor therefrom may be drawn 90 off.

2. Apparatus according to claim 1, including two ring trunks for supplying digesting liquor and make-up liquor linking up the digesters in a double ring, alternate digesters 95 being connected to the same ring trunk, and connections between said digesters and said ring trunks so arranged that alternate digesters may be operated independently in their corresponding ring circuit. 100

3. Apparatus according to claim 1, including two ring trunks linking up the digesters in a double ring, alternate digesters being connected to the same ring trunk, connections between said digesters and said ring trunks so arranged that alternate digesters may be operated independently in their corresponding ring circuit, a steam supply ring pipe, a spent liquor discharge ring pipe, and connections between said ring pipes and each 105 of the digestors. 110

4. Apparatus for the cascade extraction of cellulose pulp from fibre yielding vegetable material, comprising a plurality of digesters, two ring trunks for supplying digester liquor and make-up liquor linking up said digesters in a double ring, successive digestors being linked alternately to one and the other of said ring trunks, connections between said digestors and said ring trunks so arranged 115 that alternate digesters may be operated independently in their corresponding ring circuit and liquor in any one digester may be transferred to any other digester in the ring, a steam supply ring pipe, a spent liquor discharge ring pipe, connections between said ring pipes and each of said digestors, wash-water tanks, and connections between said tanks and said ring trunks. 120

5. Apparatus according to claim 4, includ- 125

- ing separate tanks for receiving the primary wash water and the secondary wash water, connections between said tanks and the ring trunks, said connections so arranged that wash water which has been used at least once as a secondary wash for a digester which has completed its digestion and been initially washed may be used as an initial wash for the next digester which has completed its digestion and thereafter transferred to said secondary wash water tank, and means connected to said secondary wash water tank for transferring said secondary wash water to one of the ring trunks for use as make-up liquor.
6. In a process for the cascade extraction of cellulose pulp from fibre yielding vegetable material, the steps of linking up a plurality of digesters in a double ring, by connecting them alternately to one and the other of two ring trunks, treating the material in said digesters in a plurality of stages the pressure and liquor concentration of which are progressively increased, and simultaneously flowing down from one to another of a pair of digesters connected to one ring trunk and from one to another of a pair of digesters connected to the other ring trunk.
7. In a process for the cascade extraction of cellulose pulp from fibre yielding material, the steps of linking up a plurality of digesters in a double ring by connecting them alternately to one and the other of two ring trunks, treating the material in said digesters in a plurality of stages the pressure and liquor concentration of which are progressively increased, the stages in the digesters connected to one ring trunk over-lapping those in the digesters connected to the other ring trunk, and simultaneously flowing down from one to another of at least one pair of digesters connected to the same ring trunk and discharging spent liquor from another digester.
- 45 In testimony whereof I hereto affix my signature this 11th day of January, 1928.

EDMONDSON SPENCER.
